AUTOMATIC SHAPER IN STANDARD YACHT
BUILDING

George J. Teigland, Haddonfield, N. J.

Application January 22, 1930, Serial No. 422,598
Renewed July 10, 1933

6 Claims. (Cl. 144—137)

It is very often necessary to shape planks or strips to conform to the varying contour of the ship's hull, or to conform to varying angles. In order to accomplish such work, it is essential to provide the templet with a groove or a batten so that when the groove is engaged by a templet guide, a plank may be provided with varying curvatures and angles simultaneously with the shaping of the planks.

10 It is therefore the purpose of the present invention to provide an improved shaper including a motor supporting guide, the guide adapted to vary in position, according to the angular position of the motor, a cutter being carried by the motor shaft and adapted to vary in its position according to the angular position of the motor, so as to correspond with the angular position of the guide, thereby enabling the plank or strip or similar article to be shaped as may be desired 20 in order to fulfill the construction of work at hand.

Another purpose is to provide, in a shaper of this character a templet so operable as to groove the plank or strip at the same time the plank's 25 edge is being shaped, the walls of the groove being capable of varying angularly relative to the shaped angle of the edge of the plank or strip.

Another purpose is to provide, in an apparatus of this kind, improved means, preferably of an electrical nature, though not necessarily, for actuating the templet, that is so operating it as to cause it to vary the groove being cut, in the direction of a curvature relative to the shaped edge of the plank or strip.

35 A further purpose is to embody, in a machine of the present nature, a gravity supported roller for cooperation with the plank or strip or other work to hold it in its guided position, there being tensioning means manually operated, whereby the pressure of the roller may be increased or decreased.

40 It is to be understood that the particulars herein given are in no way limitative, and that while still keeping within the scope of the invention, any desired modification of details and proportions may be made in the construction of the appliance according to circumstances.

45 The invention comprises further features and combination of parts to be hereinafter set forth, shown in the drawings and claimed.

50 In the drawings:

Figure 1 is a view in side elevation of the improved shaping machine, partly in section.

Figure 2 is a plan view of Figure 1.

55 Figure 3 is a cross sectional view on line 3—3

of Figure 1, showing the guide carried by the fixed frame of the machine, such guide adapted to receive an arcuately movable segment frame.

Figure 4 is a sectional view on line 4—4 of Figure 2.

Figure 5 is a detail plan view of a circuit closing device for operating a magnetic clutch, a worm operating alternately in either direction, with means to vary the position of the segment frame according to the character of work being 60 performed.

Figure 6 is a detail cross sectional view of Figure 5.

Figure 7 is a detailed view of a portion of a plank or strip as a sample of work accomplished.

Figure 8 is a cross sectional plan view on line 8—8 of Figure 9 with parts in elevation of a modified construction of machine.

Figure 9 is a sectional view on line 9—9 of Figure 8.

Figure 10 is a vertical sectional view on line 10—10 of Figure 9.

Figure 11 is a vertical sectional view on line 11—11 of Figure 13.

Figure 12 is a sectional plan view on line 12—80 12 of Figure 13.

Figure 13 is a vertical sectional view on line 13—13 of Figure 11.

Figure 14 is a longitudinal sectional view on the line 14—14 of Figure 7.

Referring to the drawings, 1 identifies a frame which comprises segmental pieces, in which guides in the form of channels 32 are formed. These guides or channels 32 receive the feet 4a of the motor supports 4, which in turn support the motor 2, the motor shaft 2a of which carries a revolving cutter 3.

On a screw 10 mounted in bearings 14 of the frame is a worm 11, which meshes with a worm gear 5, better shown in Figure 1 of the drawings, the worm gear 5 being in turn mounted on the shaft 31. The shaft 31 also carries two gears 6, which mesh with teeth 10a of a segment 95 4b from which the supports 4 extend. This segment with its teeth operate in the guides 32.

Obviously when the shaft 31 rotates the gear 6 likewise rotating, movement is imparted to the segment, for the purpose of adjusting the motor into different positions, and thereby dispose the cutter in different angular relations with the plank or strip which is being shaped.

A worm gear 12 is also mounted upon a screw 10, and meshes with a worm 9 on the shaft section 9a, which is located in a housing 9b. Also mounted in the housing 9b are two motors 7, the 100 105 110

- motor shafts 7a of which and the shaft section 9a carry magnetic clutches 8. When one of the clutches is in gear the screw 10 rotates in one direction which will impart movement to the 5 segment 4b in one direction. When the other clutch is in gear the screw 10 will operate in the opposite direction through the medium of the worm 9 and the worm gear 12, and then through the medium of the worm gear 5 and the worm 10 11 an opposite movement is imparted to the shaft 31, which in turn through the medium of the gears 6 will rotate the segments 4b in the opposite direction and thereby change the angle of the motor and the cutter 3.
- 15 A member 13, which may be called a nut, but which is more or less enlarged on one side and may constitute a contact element, is threaded on the screw 10.

20 Mounted on one side of the frame 1 are sprockets 19 and 20, and under the former of which a sprocket chain 21 passes. This sprocket chain 21 passes over the sprocket 20 and has attached to one of its ends a weight 22, the other end of the chain 21 is connected at 21a to one end of 25 a quadrant 15, which is carried by a shaft 35. This quadrant or segment gear is designed to be operated by the chain.

25 Spliced in the chain 21 is a plate or connector 21b, which has opposed projecting lugs or ears 30 21d and 21f, which receive the contact screws 21c, between the adjacent contact ends of which the contact element 13 operates, for closing an electric circuit over the wires or leads 26 and 27 with the electric clutches 8, the circuit not being 35 shown complete.

30 The shaft 35 which carries the segment rack or quadrant also carries a gear 18, which meshes with a gear 17 on a shaft 17a, which is mounted in bearings of the frame 1. A second gear 17c is also on the shaft 17a and meshes with the 40 rack teeth 17b on the under face of the templet guide 16, which is mounted in a suitable guide groove 16a of the table 30. The rack 16 has an 45 upstanding flange or protrusion 30a, which engages in a groove 30b of the templet 28 on which a plank, strip or other object 29 may rest while its edge is being shaped or formed.

45 Pivoted at 23a is an angle member 23, the short arm 23b of which has a notch 23c, while the 50 longer arm 23k has pivoted to it a hanger 23d. The hanger is U-shaped and depends in the direction of the plank or strip being operated on and supports a roller 25, which bears upon the 55 plank or strip to hold it in position on the templet.

55 As shown in Figure 5 suitable insulation 33 is provided for the contact screws 21c.

60 A suitable guide 36 better shown in Figure 1 is provided for guiding the templet 28.

65 The frame 1 carries bearings 24c for the reception of an adjusting screw 24, which is threaded in said bearings, and its end engages in the notch 23c. By adjusting this screw 24 in one direction or the other, it may regulate the pressure of the 65 angle member 23, namely to increase or decrease the pressure of the roller 25 on the work.

70 The work or object or piece 29 in Figure 7 partly constructed by the machine in Figures 1, 2 and 4 is formed with a beveled or inclined edge at 29a, the incline of which is reversed at its opposite ends, the inclines merging intermediately of the ends of the strip, and in constructing this edge, the protrusion or projection or upturned flange 30a of the templet guide 16 operates in the groove 75 28g of the templet 28, shown more clearly in Fig-

ures 4 and 7. Also in constructing the work or strip 29, it is the aim to provide the beveled or inclined edge 29a with a series of notches 28k and this can be accomplished through the medium of the type of machine shown in Figure 9, where the table 44 is removable, as hereinafter set forth.

80 In Figures 8 to 13 the frame 1 generally simulates the frame in the preceding figures with the exception that it is entirely circular instead of segmental, yet the circular portions have the 85 channel guides 32 for a carriage 32g. This carriage 32g comprises the supporting rods 4 for the motor bed 2h, which supports the motor, the motor shaft 2z carrying the cutter 3h, which operates on a plan 29, which is carried by a templet 90 28a, as in Figure 9.

95 In the construction in Figure 13 the templet guide has a link 42 connected to it, and said link is in turn pivotally connected to a bell crank 41, which carries a roller 40. The bell crank 41 is pivoted at 43 to the table 30 and the roller 40 operates through a slot in a table 30.

100 Rollers 36b and 36c are provided in Figure 9 for guiding the templet 28a, the roller 36c being carried by an extension of a rack 16a, and engaging 105 a slot 16k of the templet 28a. A weight 37a as in Figures 8 and 9 is provided for balancing the carriage and this weight is connected, as shown best in Figure 8, by the segments 32h. A stationary 110 locating pin 39 engages into the templet 28a, the pin 39 also engaging in a slot 44b in the table 44 for guiding the table.

115 In constructing the notches 28k in the beveled edge 29a of the strip or piece of work 29 the templet 28 as in Figure 14 is provided with a plurality of depressions 28m, which receive the locating pin 39 intermittently. In other words as the templet 28 moves, the locating pin 39 engages from one to the other of the depressions 28m, for the purpose of holding the work in position while edge notch 115 28k is cut. For example, referring more especially to Figure 9, the templet 28a is placed in position on the removable table 44, so that the rollers 36b and 36c may engage therewith, the former with one edge of the templet 28a, the latter in a slot, 120 while the pin 39 engages in the depressions 28m. The rollers 36b and 36c are provided merely for the purpose of holding the templet in position, and so is the pin 39. The depressions are cylindrical, and after a notch 28k is cut, the cutter 3h 125 is moved away from the work, and then the templet is lifted off the table 44 and placed in position so that the pin 39 may engage another depression 28m, in which case the cutter 3h is moved back in position, and in this case the work or 130 plank 29 is moved against the end of the cutter 3h thereby constructing another notch 28k.

135 However referring to Figure 4 the templet guide 16 engages in the groove 28g for guiding the templet and its work or plank 29 toward and from the cutting tool. The templet guide 16 with its upturned flange 30a is not the same as the pin 39. The pin 39 in Figure 9 engages depressions 28m, while the templet guide 16 in Figure 4 engages a guide groove 28g.

140 Springs 38 are mounted upon the rods 4 for tensioning the motor bed.

145 It is obvious that the holding means for the work can be applied to the different constructions, in Figures 8 to 13 inclusive. It is also obvious that the automatic mechanism for adjusting the motor and its support, and for adjusting the templet guide, can also be applied to Figures 8 to 13 inclusive, hence it is believed that 150

further illustration in these directions is unnecessary.

The guide 36 is carried by the table 30 and insures the prevention of the templet 28 moving 5 too close to the corner 3g of the cutter or tool. As is obvious from the showing in Figures 1 and 2 the edge or corner 3g of the cutter or tool at all times remains concentric with the center of the frame 1 of the machine, regardless of the 10 position of the segment 4b carrying the motor. For example the segment 4b may travel on a substantial arc, the edge or corner 3g of the tool or cutter at all times remaining concentric with the center of the frame 1, enabling the plank or 15 strip 29 to be given substantially any type or pitch of bevel for the purpose intended.

The same theory and mode of operation is carried out in the modifications of the principles in Figure 9, namely the cutter or tool 3h 20 operates concentric with the frame 1, which is entirely circular, the tool or cutter never engaging or contacting with the templet, which is designated by the numeral 28a in Figure 9. The springs 38 act to hold the motor in a position with 25 the cutter or tool substantially up away from the work or plank or strip being shaped.

In other words the springs 38 hold the motor in a position with the cutter up from the work, therefore when it is desired to cut the notches 30 28k the operator moves the motor down on the guides 4 in Figure 9, the cutter 3h then engages with the work or strip 29, and thereby cuts a notch. As soon as the notch 28k is cut, the pressure on the motor is relieved and then the springs 35 38 will again move the motor upward and the cutter away from the work. As previously stated it is possible to move the motor down against the action of the springs 38 and set the motor in a position as may be desired, by tightening up on the screws 4w. These springs 38 are carried by 40 the rods 4k, and operating against the collars 4m, in order to support the motor and its frame. However when it is desired to position the cutter or tool as may be necessary to perform certain work, the motor bed 2h carrying the motor 45 may be moved against the tension of the springs 38 to the required position, after which the screws 4w may be set, in order to hold the motor bed with its motor in the exact position necessary, to support the tool or cutter as might be 50 desired to produce certain shapes to the plank or strip or the like. It is obvious that in Figures 9 and 13 the segment frame with the parallel supporting rods 4k can move on a greater arc than can be assumed by the segment in Figure 1.

Referring to Figure 13 it is to be noted that the springs 38 are eliminated, and in this instance the carriage 32g which comprises the supporting rods similar to 4k are also carried by a segment 55 adjustable in the frame, which may move on a much greater arc than that in Figure 1. The rods constituting the carriage 32g support the motor bed 32k and the motor 2w, and in this construction the motor shaft carries an entirely 60 different form of tool or cutter 3w. This type of cutter or tool is especially adapted for channeling or grooving out the face of the plank or strip or the like, the channel or groove adapted to start at a very shallow depth at one end and 65 adapted to increase to a greater depth at the other end. The depth of the groove at either end or any point between the ends depends entirely on the adjustment or position of the roller 40, which also depends entirely on the adjustment 70 and position of the templet 28a in Figure 13.

In other words when the templet 28a in Figure 13 is operated through the medium of the quadrant and the electro-mechanical control as in Figure 1, the link 42 and the bell crank 41 adjusts the roller 40, thereby gauging the depth of the cut to form the groove. In order to groove or channel the face a plank or strip 46, the plank and templet are moved between the cutter or tool 3w and the upper face of the table 30, Figure 13, the shape of this groove longitudinally is shown in dotted lines in Figure 13 while its cross sectional area is shown in Figure 11.

In Figure 1 there is one form of templet 28, which is so guided as to operate the work or plank 29 in various positions toward the cutter, while in Figure 9 another form of templet 28a is shown, whereas in Figure 13 still another form of templet is shown.

It is obvious that all the templets as herein disclosed can be operated by any suitable mechanism co-operating with the rack 16 shown in Figure 1. However the quadrant and its associated parts is one preferred form of mechanism for operating various templets, the gear 17c being in direct mesh with the rack 16 in Figure 1, the 100 same engagement may be accomplished with the other racks shown in Figures 9 and 13.

While there appears to be three separate machines, such is not the case. The machines shown in Figures 9 and 13 are merely modifications, 105 and in disclosing these modifications other form of work to be accomplished has been disclosed. It is also obvious that the work performed by the construction of machine in Figures 9 and 13 can be accomplished on the construction of 110 machine shown in Figures 1, 2 and 4. Furthermore the mechanism disclosed in Figures 1 and 2 for operating the quadrant and for driving the motor and the cutter can be applied to the modified form of machines in Figures 8, 9 and 13, 115 such mechanism having been left off of the machines in Figures 9 and 13 for the purpose of simplifying illustration. In accomplishing the work performed by the construction in Figures 9 and 13, it is merely necessary to use different 120 forms of templets and different form of templet guides, these form of templets and templet guides can be applied to the machine shown in Figures 1 and 2.

In Figure 1 the work 29 is moved across the 125 face of the cutter 3, and by tilting the motor and its frame the angle of the cut on the edge of the work 29 can be varied. The fact is that the work 29 is moved by hand across the face of the cutter. It is obvious that by continuing 130 the circular shape of the frame in Figure 1 to simulate that in Figures 9 and 13, the motor 2 and the cutter 3 could be moved or adjusted to any position, such as shown in Figures 9 and 13.

In Figure 9 the plank or work 29 is supported 135 upon the templet 28a and clamped on the templet 28a in any suitable manner (not shown), and in this case the templet is operated through the medium of the rack and an associated mechanism similar to that in Figure 1 so that the 140 plank or work can move toward the cutter.

In Figure 13 a different form of templet 28 is employed, and in this instance the templet with the work or plank 46 thereon is fed by hand through the machine, and in this instance 145 the rack associated with the bell crank 41 performs a function of retaining the roller 40 in engagement with the under face of the templet, so that the plank or work 46 can be formed with a groove, the depth of the groove in the plank 150

or work 46 being determined by the depth or groove in the underface of the templet.

Various types of cutters or tools may be used and various templets, and furthermore the frame 5 in Figure 1 may be made completely circular the same as those in Figures 9 and 13.

Referring to Figures 12 and 13, in fact also to Figures 8 and 9, as well as Figures 10 and 11, the segments 4m in these figures are a part of 10 the weight 37a and can be inserted in their guides by removal of certain parts of the guides.

The guide groove 30b in Figure 1 and the guide groove 28g in Figures 4 and 7 are practically one and the same. However the guide groove 30b 15 in Figure 1 is in one type of templet while the guide groove 28g in Figures 4 and 7 is in another type of templet. The templet in Figure 1, it might be said, may be straight, and the groove 30b would extend longitudinally, therefore the 20 work 29 in Figure 1 is laterally moved and a straight edge surface cut by a tool 3, by reason of the fact that the work 29 would be moved past the tool by hand and under the roller 25, while the templet would carry the work in its 25 passage past the tool. The templet 28 as in Figure 1 would be guided by means of the groove 30b and the upstanding flange or protrusion 30a of the rack 16, while the rack through the medium of the upstanding flange or protrusion 30a 30 would hold the templet 28 against the guide 36.

It will be noted that the templet 28 in Figure 7 is of a curved contour, therefore the groove 28g in Figures 4 and 7 would be of a curved contour conforming to the curvature of the templet 35 28, that is in Figures 4 and 7.

Due to the frame of the machine having a guide concentric with the frame with means operatively adjustably supported in the guide (which is concentric with the frame) with driving 40 means to carry the tool the cutting surface of the tool radiates from the center of the frame, that is to say the cutting surface of the tool is next to the work or plank, thereby insuring its being coincident with the center of the frame. The 45 means carrying the cutting tool is always movable concentric with the frame, and due to this, and the fact that the cutting surface of the tool immediately adjacent the plank or work is always coincident with the center of the frame, the means 50 carrying the tool can automatically operate as in Figure 1, or may be moved by hand as may be accomplished in Figures 9 and 13, and when moved automatically as in Figure 1, a beveled surface such as disclosed at 29a may be imparted to the 55 work or plank 29. In other words a bevel inclined in one direction at one end of the work 29, and inclined in the opposite direction at the other end of the work 29.

80 The invention having been set forth, what is claimed is:

1. In an automatic shaper, the combination with a frame having guide channels disposed in circular position, of a segment member in the guide channels, a motor including a cutter on its shaft supported on the segment, the frame having a table, a templet guide associated with the table, electro mechanical means operatively connected with the segment and the templet guide 65 for automatically adjusting the templet guide and the segment, whereby the templet guide may adjust itself according to the position of the cutter, which also positions itself in accordance with the adjusted position of the segment for applying the desired shape to the work, a templet asso-

ciated with the templet guide, and a second guide for the templet.

2. In an automatic shaper, the combination with a frame having guide channels disposed in circular position, of a segment member in the guide channels, a motor including a cutter on its shaft, supported on the segment, the frame having a table, a templet guide associated with the table, electro mechanical means operatively connected with the segment and the templet guide for automatically adjusting the templet guide and the segment, whereby the templet guide may adjust itself according to the position of the cutter, which also positions itself in accordance with the adjusted position of the segment for applying the desired shape to the work, a templet associated with the templet guide, and a second guide for the templet, and means for bearing upon the work supported on the templet to retain the work in position adjacent the cutter. 80 85 90 95

3. In an automatic shaper, the combination with a frame having guide channels disposed in circular position, of a segment member in the guide channels, a motor including a cutter on its shaft supported on the segment, the frame having a table, a templet guide associated with the table, electro mechanical means operatively connected with the segment and the templet guide for automatically adjusting the templet guide and the segment, whereby the templet guide may adjust itself according to the position of the cutter, which also positions itself in accordance with the adjusted position of the segment for applying the desired shape to the work, a templet associated with the templet guide, and a second guide for the templet and means for bearing upon the work supported on the templet to retain the work in position adjacent the cutter. 100 105 110

4. In an automatic shaper, the combination with a frame having arcuate opposed channel guides and provided with a table, of a templet operable on the table, an adjustable templet guide, a motor having a shaping tool to operate against the work supported on the templet, means in the channel guides for supporting the motor, and a mechanism automatically and alternately 120 reversible and operatively connected with the templet guide and the means in the channels for adjusting the position of the templet guide and the motor including its shaping tool, for governing the character of shape to be applied to the 125 work. 130

5. In an automatic shaper, the combination with a frame having arcuate opposed channel guides and provided with a table, of a templet operable on the table, an adjustable templet guide, a motor having a shaping tool to operate against the work supported on the templet, means in the channel guides for supporting the motor, and a mechanism automatically and alternately 140 reversible and operatively connected with the templet guide and the means in the channels for adjusting the position of the templet guide and the motor including its shaping tool, for governing the character of shape to be applied to the work, means for bearing on the work to retain it 145 on the templet in position adjacent the tool.

6. In an automatic shaper, the combination with a frame having arcuate opposed channel guides and provided with a table, of a templet operable on the table, an adjustable templet guide, 150

a motor having a shaping tool to operate against the work supported on the templet, means in the channel guides for supporting the motor, and a mechanism automatically and alternately reversible and operatively connected with the templet guide and means in the channels for adjusting the position of the templet guide and the motor

including its shaping tool, for governing the character of shape to be applied to the work, means for bearing on the work to retain it on the templet in position adjacent the tool, and manual means for increasing and decreasing the pressure of said holding means.
